UNITED STATES PATENT OFFICE.

HETTA E. HUNTER, OF WASHINGTON, DISTRICT OF COLUMBIA.

DESIGN FOR A STUDENT'S CHAIR.

SPECIFICATION forming part of Design No. 25,074, dated January 21, 1896.

Application filed December 14, 1895. Serial No. 572,222. Term of patent 7 years.

To all whom it may concern:

Be it known that I, HETTA E. HUNTER, a citizen of the United States, residing at Washington city, District of Columbia, have invented or produced a new and original Design for Students' Chairs, of which the following is a specification.

This design has for its object to provide a novel, handsome, and ornamental student's chair which presents a peculiar and characteristic appearance to the eye.

The leading feature of the design consists in a student's chair having a flat seat, a straight upright back, a side arm composed of a narrow shank portion joined to the chair-back and portions widened laterally to project in opposite directions from the shank portion with one of the widened portions of greater length than the other and extending over the front part of the chair-seat, and front chair-legs, one terminating at the chair-seat and the other rising above the seat to the widened portion of the side arm.

The design is illustrated by the accompanying drawing, in which the figure is a perspective view of my new and original student's chair.

In the drawing illustrating the design, the numeral 1 indicates the flattened chair-seat, and 2 and 3 the upright side pieces of the chair-back connected at their top portion by an ornamental transverse panel 4 and at a point directly above the rear part of the flattened chair-seat by a transverse panel 5, somewhat narrower than the ornamental panel 4. The space between the two panels is occupied by a plurality of ornamental rounds 6.

The chair is armless at one side, but at the opposite side is provided with a side arm composed of a comparatively narrow shank 40 portion 7 and portions 8 and 9 widened at right angles to and projecting in opposite directions from the shank portion and extending in an inclined plane in a downward direction from the end of the portion 8 to the 45 end of the portion 9, which latter is of a greater length than the former, and is arranged over the front part of the chair-seat.

The chair is provided at the front with two cylindrical legs 10 and 12. The leg 10 extends to and terminates at the chair-seat, while the leg 12 extends above the chair-seat and joins the laterally-widened portion 8 of the side arm. An inclined rod 13 extends from the leg 12 at a point above the chair-seat to the under side of the widened portion 9 of the side arm.

My design provides a new and original student's chair which is handsome and ornamental and presents a very characteristic and 60 attractive appearance to the eye.

What I claim is—

The design for a student's chair, substantially as shown and described.

In testimony whereof I have hereunto set 65 my hand in presence of two subscribing witnesses.

HETTA E. HUNTER.
